Primary Examiner — David G Muller*(74) Attorney, Agent, or Firm* — Birch, Stewart, Kolasch & Birch, LLP(57) **CLAIM**

The ornamental design for a humidifying air purifier as shown and described.

DESCRIPTION**1.1** : Perspective**1.2** : Front**1.3** : Back**1.4** : Left**1.5** : Top**1.6** : Bottom**1.7** : Front perspective view

The broken lines depict portions of the humidifying air purifier that form no part of the claimed design; this design is for a humidifying air purifier; as shown in reproduction **1.7**, this design can adjust the height of the upper part where the humidification outlet is located, so that the user can control the humidification according to the space and condition; reproduction **1.3** is a left view where the right view is a mirror image; reproduction **1.7** is a front perspective view showing the use state when the upper part has been moved upward.

1 Claim, 7 Drawing Sheets(56)
